[57] CLAIM

The ornamental design for a lamp shade holder, as shown and described.

DESCRIPTION

FIG. 1 is a perspective view showing my new design, the phantom lines depicting broken-away struts on which a lamp shade is supported the phantom lines being shown for illustrative purposes only and forming no part of the claimed design;

FIG. 2 is a top plan view thereof;

FIG. 3 is a front elevational view thereof;

FIG. 4 is a left side elevational view, the right side elevational view being a mirror image;

FIG. 5 is a rear elevational view thereof; and,

FIG. 6 is a bottom plan view thereof.
